UNITED STATES PATENT OFFICE

JOSEPH H. POPE, DECEASED, LATE OF HAMILTON, MASSACHUSETTS, BY ELMER R. POPE, EXECUTOR, OF HAMILTON, AND JOHN B. HADADAY, OF SWAMPSCOTT, MASSACHUSETTS, ASSIGNORS TO UNITED SHOE MACHINERY CORPORATION, OF PATERSON, NEW JERSEY, A CORPORATION OF NEW JERSEY

HEELING MACHINE

Application filed February 18, 1928. Serial No. 255,436.

This invention relates to heelng machines, and particularly to the work supporting and presenting mechanisms of such machines.

An object of the invention is so to improve the arrangement of the shoe supporting, pressure applying, and heel holding elements of heelng machines as to facilitate the insertion into the machine of the work parts and the accurate relative positioning and attachment of such parts to each other.

In a well known and widely used type of machine, the lightning heeler, the shoe supporting jack is arranged to slide from an accessible, work receiving position to an operating position beneath a stationary nailing die, the lower face of which engages and applies pressure to a heel supported in a heel holder located between the die and the jack, in fact practically against the lower face of the die. The heel holder facing downward and being below the normal line of vision of the operator, the heel is inserted principally by the sense of touch.

In accordance with the present invention the nailing die is made movable from a heel receiving position, in which its work engaging face, with the heel holder thereon, is exposed to view and is easily accessible, to a heel nailing position, which it occupies while the heel attaching nails are being driven.

Preferably the die is so connected to the movable shoe supporting jack of the heelng machine that the die derives its movement from the movement of the jack and, in this connection, a feature of the invention resides in an improved organization of mechanism of the character described in which the nailing die is movable about an axis passing through said die.

By virtue of this the great strength necessary in heelng machines is secured without the sacrifice of compactness which would be entailed in other arrangements.

Furthermore, it is essential, for obvious reasons, that the holes in the die be in exact alinement with the nail drivers when the drivers are operated to enter said holes and drive the nails, but a slight amount of lost motion in the connections between the jack and the die will destroy the accuracy of the

alinement produced by positioning the jack, to a dangerous extent. Another feature of the invention, accordingly, consists in the provision of a fixed abutment arranged to be engaged directly by the die to determine accurately the nailing position of the die. The determination of the nailing position of the die is thus made positive and danger of inexact positioning of the die, by reason of looseness resulting from wear or any other cause, is eliminated. In the illustrated machine the connections between the jack and die are made sufficiently yielding to permit the movement of the die to be stopped by the abutment before the end of the inward movement of the jack, assuring that the die will unfailingly engage the abutment and be properly positioned for use.

A further feature of the invention, contributing to accuracy and certainty in the functioning of the mechanism, consists in a normally inoperative lock arranged to co-operate with the nailing die to lock it in nailing position, combined with means whereby movement of the jack causes the lock to operate. An efficient embodiment of this feature is shown in the accompanying drawings wherein is illustrated a machine in which the nailing die lock is connected to and operated by a lock actuator constituting a back gage arranged to be engaged by the jacked shoe when the jack is moved into operating position.

These and other features and advantages of the invention will be better understood and appreciated by reading the following detailed description of one embodiment thereof in connection with the accompanying drawings, in which,

Fig. 1 is a view in side elevation, partly in section, of heelng machine mechanism embodying the invention, the parts being shown in work receiving position;

Fig. 2 is a similar view showing the parts in operating position; and

Fig. 3 is a view, partly in elevation and partly in section, looking from the front of the machine.

The machine comprises the usual stationary side rods 10 (Fig. 3) rigidly spaced

from each other by a stationary connecting yoke 12; and a vertically reciprocable cross head 14 which carries the shoe supporting jack. For a complete disclosure of the structure of those parts of the machine not herein illustrated reference may be made to United States Letters Patent No. 446,885, granted Feb. 24, 1891, upon application of Joseph H. Pope.

10 Horizontal inwardly extending trunnions 16 are mounted upon the side rods 10, as shown in Fig. 3, and constitute supports about which a nailing die 18 is adapted to move around a horizontal axis passing through said die. The construction and arrangement are such that the die 18 is movable, about the axis of the trunnions 16 from the position shown in Fig. 1, in which the heel engaging face of the die faces outward and upward 15 toward the front of the machine, to the position shown in Figs. 2 and 3, in which the heel engaging face of the die faces downward.

A shoe supporting jack 20 is mounted for pivotal movement about trunnions 22 upon the cross head 14 from the work receiving position shown in Fig. 1, where it is accessible for the jacking or removal of a shoe, to the operating position shown in Fig. 2, where it is beneath the nailing die. The 25 jack is, as usual, moved into and out of the machine by hand.

In order to effect the desired movements of the nailing die between work receiving and operating positions, movement transmitting connections are provided between the movable jack and the movable die. As herein shown these connections comprise a two-part link 23, one end of which is pivoted to the nailing die 18 at 24 and the other 30 end of which is pivoted to the jack member at 26. The nailing die is recessed, as shown at 25, to avoid interference between the die and the link in operation. The two sections of the link are telescopically arranged, as shown in Fig. 1, a compression spring 28 being interposed between the two sections of the link and permitting a small amount of yield lengthwise thereof. The rear face 30 of the nailing die 18 is arranged to abut 35 against the front face 32 of a stationary bracket 34 to limit positively the movement of the nailing die, as it reaches operating position. From the foregoing it will be apparent that movement of the jack 20 into 40 and out of the machine will be transmitted by the connecting link 23 to the nailing die and will cause movement of the die between the two positions shown in Figs. 1 and 2.

A threaded adjustment 36 permits variation 45 of the length of the link 23, which is so determined that the nailing die engages and is stopped by the surface 32 just before the jack reaches the rearward limit of its movement, the spring 28 yielding to permit 50 the remainder of such movement.

In order to insure accuracy in the operating position of the nailing die and to avoid any possibility of moving when pressure is applied there are provided tapered locking bolts 38 which enter correspondingly tapered holes 40 in the rear face 30 of the die. The bolts are slidably mounted in guide holes formed in the bracket 34 and are actuated by arms 42 secured to a rock shaft 44 to which is also secured a depending lever 46. The lever 46 engages the rear face of a nut 48 threaded upon a horizontally movable screw 50, the limits of movement of the screw being determined by spaced, stationary uprights 52, 54 through which the screw 50 moves. To the front end of the screw 50 is pivoted a guide plate 56 upon which a back gage 60 is vertically slidable. The said back gage is supported by a bar 62, the lower end of which is pivoted at 64 to a bracket 66 bolted to and movable with the cross head 14. The back gage 60, therefore, moves up and, by virtue of the pivotal connection 64, can be moved rearward by the jacketed shoe to a position determined by the adjustment 90 of the nut 48 upon the screw 50.

Also secured to the rock shaft 44 is a forwardly disposed arm 68 which is connected by a link 70 to a rocker arm 72 movable about a stationary pivot 74. A pull spring 76, connected to the link 70 and the bracket 34, tends normally to elevate the link and, consequently, to move the locking bolts 38 rearward and the back gage 60 forward.

The rocker arm 72 is connected to and operates a clutch stop rod 78, the lower end of which co-operates with a dog 80 to prevent operation of the clutch engaging shaft 82 to apply power to the machine when the shoe is not in operating position therein, in a manner already known to those skilled in the art.

A heel holder suitable for the type of heel to be attached is secured to the heel engaging face of the nailing die 18 and partakes of the movements of the latter. The present machine is illustrated as equipped to attach a heel consisting of an assembled rubber top lift 80 and a base 82 and the holder consists of a ring or a form 84, in which the rubber heel section fits closely, held in place on the lower face of the nailing die by a flange 86 and a spring actuated latch 88.

The machine is normally stopped with the mechanism disposed as shown in Fig. 1, the heel holder facing outward and upward toward the operator's eyes and access to the holder being entirely unobstructed. A lasted shoe 90 is placed upon the shoe supporting jack and a heel is inserted in the heel holder, against the face of the nailing die. The jack is now moved rearward until the shoe engages and is stopped by the rear gage 60. The inward movement of the jack effects a move-

ment of the nailing die and heel holder to the position shown in Fig. 2 where the heel is supported above the shoe ready to be pressed thereon. The last part of the inward movement of the jack has, as hereinbefore described, caused the screw 50 to be moved rearward and the lock 38 to be operated to lock the nailing die in operating position; it has also caused the rod 68 to be retracted, unlocking the shaft 82 and permitting the clutch controlled thereby to be engaged to effect the power operation of the heel attaching mechanism of the machine in the usual manner. When this operation is complete and the pressure is released the operator returns the jack 20 to the position shown in Fig. 1, the nailing die 18 being unlocked and also returning to work receiving position without any attention from the operator. The shoe, with the attached heel, is now removed from the jack and the machine is ready for a repetition of the operation upon another shoe.

Having described the invention, what is claimed as new and desired to be secured by Letters Patent is:

1. In a heel attaching machine, the combination of a movable shoe support, a nailing die movable about an axis passing through said die, and connections between said support and said die constructed and arranged to transmit movement of the support to the die.
2. In a heel attaching machine, the combination of a movable jack, a nailing die movable to and from a heel nailing position, a normally ineffective lock arranged to co-operate with the die to lock it in nailing position, and means whereby movement of the jack causes the lock to operate.
3. In a heel attaching machine, the combination of a movable jack, a nailing die movable to and from a heel nailing position, a lock co-operating with the die to lock it in nailing position, means whereby movement of the jack causes the die to move to nailing position and additional means actuated by movement of the jack to cause the lock to operate to lock the die in said position.
4. In a heel attaching machine, the combination of a movable shoe support, a movable nailing die, a lock co-operating with the die, and a lock actuator arranged to be engaged by a shoe upon said support.
5. In a heel attaching machine, the combination of a movable shoe support, a movable nailing die, a lock co-operating with the die, a movable back gage arranged to be engaged by a shoe upon said support, and connections between the back gage and the lock constructed and arranged to transmit movement of the gage to the lock.
6. In a heel attaching machine, the combination of a movable jack, a nailing die movable to and from a heel nailing position, connections between the jack and die con-

structed and arranged to transmit movement of the jack to the die, and a fixed abutment arranged to be engaged directly by the die to determine accurately its nailing position.

7. In a heel attaching machine, the combination of a jack movable from work receiving position to heel nailing position, a nailing die movable to and from a heel nailing position, yielding connections between the jack and die so constructed and arranged that movement of the jack to nailing position causes movement of the die to nailing position, and a fixed abutment arranged to stop the die accurately in a predetermined nailing position before the jack reaches its nailing position.

8. In a heel attaching machine, the combination of a jack movable to and from heel nailing position, a nailing die movable to and from a heel nailing position, a yieldable link connecting the jack and die to transmit movement from the jack to the die, and a fixed abutment arranged to be engaged by the die and to stop movement of the die before the end of the movement of the jack to nailing position.

In testimony whereof I, the said ELMER R. POPE, have signed my name to this specification.
